UNITED STATES PATENT OFFICE.

CLARE L. SEMANS AND EDWARD C. HEILIGMAN, OF DALLAS, TEXAS.

MILITARY OR SIMILAR INSIGNIA.

1,282,471.

Specification of Letters Patent. Patented Oct. 22, 1918.

Application filed June 29, 1918. Serial No. 242,600.

To all whom it may concern:

Be it known that we, CLARE L. SEMANS and EDWARD C. HEILIGMAN, citizens of the United States, residing at Dallas, in the county of Dallas and State of Texas, have invented certain new and useful Improvements in Military or Similar Insignia, of which the following is a specification.

Our invention has relation to an improvement in the manufacture of military or similar insignia and in such connection it relates more particularly to the arrangement and parts of the insignia.

Heretofore it has been customary to embroider on stiffened broadcloth or similar fabric and with metallic cloth or yarn the design of insignia desired and such cloth so embroidered was thereafter tightly drawn around so as to inclose a rigid base and the cloth edges sewed together. The defects of such a structure, aside from the cost and labor involved, are many, the principal being that the cloth and embroidery rapidly disintegrate under wear and tear and the design is easily tarnished and soon obliterated, and destroyed.

We have discovered that by forming the design in a plurality of sections, each section being stamped or otherwise formed from a plate of metal, silver, gold, or the like and in assembling these sections on a cloth covered, rigid, base in proper relationship and in then uniting the plates to the base by prongs or fastening devices projecting from said plates and traversing the cloth and the rigid base, an insignia will result which has all the essential characteristics of the cloth embroidered insignia, but is practically indestructible in use and wear.

By so forming the design of the insignia in separable sections we are also enabled to form said plates with a suitable form of base, those variations of the design of the insignia which are desired by the military or naval authorities to indicate various grades of authority in the line of service for which said insignia has been prescribed.

The nature and scope of our invention will be more fully understood from the following description taken in connection with the ac-

companying drawings forming part hereof, in which—

Figure 1 is a front view of an insignia embodying the main features of our invention.

Fig. 2 is a cross sectional view taken on line 2—2 of Fig. 1.

Fig. 3 is a similar view taken on line 3—3 of Fig. 1.

Fig. 4 is a front view of a variation in form of the insignia embodying our invention, and

Fig. 5 is a rear view of the insignia.

In the drawings we have illustrated the insignia as one used to designate an officer and an observer in the aviation corps of the Army. It is manifest, however, that our invention may be embodied in varying designs of insignia for other branches of the service whether military or naval, the design being unimportant and not a limitation upon our invention.

Referring to the drawings, a rigid base 1 usually of brass or similar metal, is inclosed in broadcloth or similar material 2, the cloth being tightly drawn over the metal base and the edges being stitched together as at 3, Fig. 5, to fasten the cloth to the base.

The base 1 is provided at required points with slots or openings 4.

The design of the insignia is formed of a plurality of plates the design of which as shown in the drawings are the two wings 5 separated by a shield 6 to indicate an officer in the aviation section. Each plate 5 or 6 is stamped or embossed as required and from the concave face of each plate 5 or 6 project the prongs 7 designed to traverse the cloth 2 and the slots or perforations 4, and to be bent back as at 8 (Fig. 2) down upon the rear face of the base 1 to lock or fasten the plates 5 and 6 to the base and down upon the cloth covered face of said base.

When desirable, the rear face of the rigid base 1 may be provided with a pin 9 and catch 10 to convert the insignia into a brooch like pin or ornament.

Where, as in Fig. 4, the plates 5 and 6 are to be assembled to indicate that the wearer is an observer in the corps, one wing 5 is

discarded, and the design is made up of the shield 6 and one wing 5 to the right of said shield. Of course under all conditions the rigid base is shaped to correspond with the outline of the completed insignia, the base 1 extending from wing to wing in Fig. 1 and from shield to wing in Fig. 4.

To protect the prongs 7 against wear or accidental detachment, the cover of cloth 2 should be so sewed to the base 1 as to cover the prongs.

Having thus described the nature and objects of our invention, what we claim as new and desire to secure by Letters Patent, is—

1. The improvement in the manufacture of insignia which consists in first forming the design from a plurality of detachably arranged metallic plates, each plate being stamped or embossed with the design de-

sired, then forming the rigid base with a contour required by the design, then covering said base with cloth and finally uniting the plates to the base by fasteners traversing the cloth and united to the rear face of said base. 25

2. In an insignia, a series of embossed metal plates, a plurality of prongs projecting from the rear concave face of each plate, a rigid base perforated to receive the prongs and a covering of fabric inclosing the base, 30 said covering adapted to be traversed by the prongs in the fastening of said plates to said base.

In testimony whereof we have signed our names to this specification.

CLARE L. SEMANS.
EDWARD C. HEILIGMAN.
